Primary Examiner — Nathan M Johnston

(74) Attorney, Agent, or Firm — George D. Morgan

(57) **CLAIM**

The ornamental design for a car tissue holder, as shown and described.

DESCRIPTION

FIG. 1 is a top perspective view of a car tissue holder, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Broken lines are used to illustrate portions of the car tissue holder that form no part of the claimed design. The dash dot lines represent stitching and form part of the claimed design.

1 Claim, 8 Drawing Sheets
